UNITED STATES PATENT OFFICE.

FREDERICK G. SARGENT, OF WESTFORD, MASSACHUSETTS, ASSIGNEE TO C. G. SARGENT'S SONS CORPORATION, OF GRANITEVILLE, MASSACHUSETTS, A CORPORATION OF MASSACHUSETTS.

WRINGER-ROLLS.

1,182,420.

Specification of Letters Patent.

Patented May 9, 1916.

Application filed February 24, 1913. Serial No. 750,328.

To all whom it may concern:

Be it known that I, FREDERICK G. SARGENT, a citizen of the United States, residing at Westford, in the county of Middlesex and State of Massachusetts, have invented new and useful Wringer-Rolls, of which the following is a specification.

This invention relates to the wringer rolls of washing machines but is capable of application to any set of wringer or extractor rolls.

The principal objects of the invention are to provide a construction by which certain kinds of stock, such as pulled cattle hair and the like, can be passed through the rolls in a successful manner. Stock of this kind is passed through ordinary rolls with difficulty as it is of an irregular character and contains bunches and hard compact masses of hair.

This invention is designed to do away with this difficulty and at the same time provide a set of rolls suitable for general use, but particularly applicable to wool and hair washing machines in which a slight space can be left between the adjacent surfaces of the two rolls.

Reference is to be had to the accompanying drawing, in which—

Figure 1 is a front elevation of a pair of wringer rolls and the supports therefor, showing one of the rolls partly in longitudinal section, and Fig. 2 is a similar view of a modification.

This invention involves the use of a pair of rolls, one of which consists of a core or mandrel of hard material covered with soft rubber or lapping and the other of which has a hard surface. At the ends of one roll means are provided for bearing directly on the other roll with some pressure, while the intermediate portion is spaced from it or bears with a light pressure. Either the bottom roll or the top roll can be made in this way, or both.

In Fig. 1 the invention is shown as applied to a wool and hair washing machine having a bottom roll 10 of iron or steel which may be covered with a brass jacket. At the end this roll is provided with a pair of circumferential grooves 11 to receive the liquid squeezed out at its upper surface and to prevent its running on the bearings.

The upper roll in Fig. 1 shows a preferred embodiment of this invention. The roll is

mounted on a shaft 12 and has a central mandrel 13. At the ends of this mandrel are a pair of hard rubber rings 14 and between these rings the mandrel is covered with soft rubber or lapping 15 which is slightly smaller in diameter than the hard rubber rings. If lapping is used it is in the form of worsted stubbing wound on between the raised flanges 14. Of course any other soft material usually employed on rolls of this character can be substituted for the soft rubber. The ends 14 can be in the form of disks or of rings covering the ends of mandrel 13. The hard rubber rings 14 rest upon the roll 10 and the hair or wool can be put through the rolls under all ordinary conditions, because the hard rubber ends keep the soft rolling surface 15 slightly away from the surface of the roll 10 and the pressure, when there is no stock between the rolls, is received at the ends of the rolls.

In Fig. 2 the invention is shown as applied to a plain rubber-covered top roll 20 and a hard bottom roll 21. The ends 22 of the bottom roll support the top roll. The bottom roll has a slight depression 23 to enable the pair of rolls to take the material into the bite thereof.

Although I have illustrated and described only two embodiments of the invention, I am aware of the fact that other modifications can be made therein without departing from the scope of the invention as expressed in the claim. Therefore, I do not wish to be limited to the exact details of construction shown, but

What I do claim is:—

In a wringer, the combination with a roll having a straight cylindrical metallic surface, of a second roll adapted to rotate in contact therewith and provided with hard end flanges and having a relatively soft intermediate portion extending from one of said flanges to the other, said flanges being of slightly greater diameter than the intermediate portion, whereby the latter is spaced from the first mentioned roll.

In testimony whereof I have hereunto set my hand, in the presence of two subscribing witnesses.

FREDERICK G. SARGENT.
